CLAIM

The ornamental design for a hearing protector, as shown and described.

DESCRIPTION

FIG. 1 is a perspective view of a hearing protector showing our new design;

FIG. 2 is a right side view thereof;

FIG. 3 is a left side view thereof;

FIG. 4 is a front view thereof;

FIG. 5 is a top view thereof;

FIG. 6 is a bottom view thereof; and,

FIG. 7 is a rear view thereof.

Portions of the drawings shown in broken lines do not form part of the claimed design.
